US0D1111836S

(12) **United States Design Patent** (10) **Patent No.:** **US D1,111,836 S**
(45) **Date of Patent:** ** *Feb. 10, 2026

(54) **BOTTLE**

(71) Applicant: **INDUSTRIAS ALEN, S.A. DE C.V.**,
Santa Catarina (MX)

(72) Inventor: **Cristina Julieta Castro-Flores**, Santa
Catarina (MX)

(73) Assignee: **INDUSTRIAS ALEN, S.A. DE C.V.**,
Santa Catarina (MX)

(*) Notice: This patent is subject to a terminal disclaimer.

(**) Term: **15 Years**

(21) Appl. No.: **29/952,460**

(22) Filed: **Jul. 16, 2024**

Related U.S. Application Data

(63) Continuation of application No. 29/824,688, filed on
Jan. 26, 2022, now Pat. No. Des. 1,041,315.

(57) **CLAIM**

The ornamental design for a bottle as shown and described.

DESCRIPTION

FIG. 1 is a perspective view of a bottle showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines depict portions of the bottle that form no part of the claimed design.

1 Claim, 5 Drawing Sheets
